DESIGN FOR A BROOCH OR SIMILAR ARTICLE

Max Le Brun, Woodmere, N. Y.

Application August 13, 1940, Serial No. 94,399

Term of patent 3½ years

To all whom it may concern:

Be it known that Max Le Brun, a citizen of United States and resident of Woodmere, in the county of Nassau and State of New York, has invented a new, original, and ornamental Design for a Brooch or Similar Article, of which the following is a specification, reference being had to the accompanying drawing, forming part thereof, and in which,

Fig. 1 is a top plan view of a brooch or similar article, embodying my new design; and
Fig. 2 is a top edge view thereof.

I claim:

The ornamental design for a brooch or similar article, substantially as shown.

MAX LE BRUN.
